(57) **CLAIM**

The ornamental design for an anchor pad, as shown and described.

DESCRIPTION

FIG. 1 is an isometric view of the anchor pad of the present invention, illustrated with its release liner shown in broken lines;

FIG. 2 is a top plan view of the anchor pad as shown in FIG. 1 with an upper cover disposed above a well;

FIG. 3 is a bottom plan view of the anchor pad as shown in FIG. 1;

FIG. 4 is a rear elevational view of the anchor pad as shown in FIG. 1;

FIG. 5 is a front elevational view of the anchor pad as shown in FIG. 1;

FIG. 6 is a right side elevational view of the anchor pad as shown in FIG. 1, the left side view being a mirror image of the illustrated view;

FIG. 7 is an isometric view of the anchor pad of the present invention, illustrated with the upper cover removed to expose the well;

FIG. 8 is a top plan view of the anchor pad as shown in FIG. 7;

FIG. 9 is a bottom plan view of the anchor pad as shown in FIG. 7;

FIG. 10 is a rear elevational view of the anchor pad as shown in FIG. 7;

FIG. 11 is a front elevational view of the anchor pad as shown in FIG. 7; and,

FIG. 12 is a right side elevational view of the anchor pad as shown in FIG. 7, the left side view being a mirror image of the illustrated view.

The broken line showing in the FIGS. 1 through 12 are for illustrative purposes only and forms no part of the claimed design.

1 Claim, 4 Drawing Sheets
